(57) **CLAIM**

The ornamental design for a fragrance diffuser with fragrance cartridge, as shown and described.

DESCRIPTION

FIG. 1 is a front view of a fragrance diffuser with fragrance cartridge according to our new design;

FIG. 2 is a rear view thereof;

FIG. 3 is a first side view thereof;

FIG. 4 is a second side view thereof;

FIG. 5 is a top view thereof;

FIG. 6 is a bottom view thereof;

FIG. 7 is a top perspective thereof;

FIG. 8 is a bottom perspective view thereof;

FIG. 9 is a front view of a fragrance diffuser with fragrance cartridge according to our new design with the cartridge shown enlarged and by itself for ease of illustration, the rear view being a mirror image thereof;

FIG. 10 is a first side view thereof, the second side view being a mirror image thereof;

FIG. 11 is a top view thereof;

FIG. 12 is a bottom view thereof;

FIG. 13 is a top perspective thereof; and,

FIG. 14 is a bottom perspective view thereof.

The broken lines shown in the figures are for the purpose of illustrating portions of the fragrance diffuser with fragrance cartridge and form no part of the claimed design.
